AUTOMATIC CONTROL FOR INTERNAL COMBUSTION ENGINES

John F. Campbell, Dayton, Ohio

Application October 26, 1931, Serial No. 570,994

3 Claims. (Cl. 123—103)

This invention relates to improvements in means for controlling the admission of fuel to internal combustion engines, and has for its object to provide a device or apparatus that will deliver fuel of a predetermined mixture strength under conditions of varying loads or speeds.

It is an object of this invention to provide control means for internal combustion engines that is responsive to changes in air density at varying altitudes and changes in the pressures in the induction system of the engine so as to maintain the desired predetermined mixture strengths, thereby making a mechanical linkage between the fuel charger and the air throttle unnecessary.

It is also an object of this invention to provide a control means for internal combustion engines for keeping the fuel charger lever in a no delivery or a safety position while the engine is not in operation, but it may be shifted to provide for the desired increase charge while cranking.

It is a further object of this invention to provide an automatic control for internal combustion engines which makes for simple installation on the unit which it controls and operates.

These and other advantages will appear from the following description taken in connection with the drawings, in which there is shown a preferred embodiment.

Referring to the drawings:

Figure 1 is a view showing a part of the motor ring, a part of the starter, the fuel charger, and an automatic control connected thereto.

Figure 2 is a longitudinal section through the automatic control for internal combustion engines.

Figure 3 is a fragmentary section on the line 3—3 of Figure 2.

Figure 4 is a view of the bracket structure used in connection with the metallic bellows for operating the helix shaft.

Figure 5 is an end elevation of Figure 4.

The present automatic control for internal combustion engines is adapted to be used with any engine of the internal combustion type, but is particularly designed and well adapted for use in connection with airplane engines. In the present drawings it is shown in connection with the mounting ring 1 of an airplane.

On one side of this ring and properly supported in connection therewith is a starter 2 used for starting purposes. Connected with the starter and suitably supported by the ring and the engine supported thereby is a gear reduction box

3 used to house the gearing for connecting the mechanism for operating the fuel or gas delivery and distributing means. The numeral 4 is used to designate the mounting flange of the engine.

The device is mounted, by preference in the present instance, directly to the unit to be controlled by means of mounting pads 5. The apparatus is shown properly mounted in its proper surroundings in Figure 1. In Figure 2 there is a longitudinal section. In this section and also in Figure 1 there is shown a fuel charger 6, which may be of any desired and suitable form and character. Extending from a movable part of this fuel charger is a bracket 7, to which one end of a piston rod 8 is attached by means of a pin 9 fitting in a slot 10 in the bracket 7.

On the inner end of the piston rod 8 is a piston 11 working in a cylinder 12, which constitutes an oil pressure cylinder. On the piston is an apron 13 projecting in a slot 14 in one side of the cylinder 12. Between the piston 11 and one end of the cylinder 12 is a spring 15. Extending through the front end of the cylinder 12 is an oil inlet 16, which is connected to the oil pressure line from the engine for transmitting oil pressure to the cylinder 12 against the piston 11. The position of the piston 11 in the cylinder depends upon the spring 15 and the oil pressure against the piston, and also upon the position of a hollow metering valve 17 located adjacent the cylinder 12 and along the slot 14.

This metering valve has a spiral slot 18 around the metering valve so that in whatever position the metering valve may be the spiral slot 18 will cross at some point the slot 14, so that oil pressure will pass from the cylinder 12 through the two slots into the hollow metering valve, and out through a drain line at the lower end thereof. Whenever the oil passes out through these two slots pressure against the piston is released so that the spring will force the piston toward the oil pressure opening 16 and will force the piston to a point that there is left merely a bleed opening between the two slots. If the pressure becomes great this pressure on the piston will cause a larger opening between the two slots, thereby diminishing the pressure in the cylinder against the spring so that the spring moves the piston to reduce the outlet between the two slots, thereby increasing a condition of equilibrium between the spring and the oil pressure.

At each end of the hollow metering valve are bearings 19 to support this valve so that it may readily rotate for bringing the spiral slot in proper position with relation to the slot 14 and

the piston 11. On one end of the hollow metering valve and beyond the bearings thereon is a pinion 20 meshing with a gear 21 on a shaft 22. This shaft 22 is mounted in bearings 23. To this shaft 5 is suitably attached a helix shaft 24, which has on opposite sides thereof spiral, flat surfaces 25. This helix shaft projects into a pressure chamber 26.

The above described shaft 22 and helix shaft 10 24 are located in one end of the pressure chamber, while in the other end and suitably attached thereto, is a metallic bellows 27. The inner end of this metallic bellows has a cup-shaped member 28, on the outer end of which are brackets 29. 15 At the inner ends of these brackets, which project within the cup member 28, is a cylindrical member 30. This cylindrical member 30 has holes 31 therein to receive and permit rotative movement of the helix shaft 24 and longitudinal movement 20 of the metallic bellows 27 and brackets 29.

In the cylindrical member are two rollers, one 32 and the other 33, engaging the spiral flat sides of the helix shaft. These rollers are inclined in regard to the axis of the helix shaft so that each 25 roller engages a spiral flat side so that each roller is seated and held at the normal angle with respect to the side that it engages. By this means it is impossible to move the metallic bellows without consequent angular movement of the helix 30 shaft. In other words, the arrangement of the rollers with respect to the helix shaft does not permit back lash or false movement. Also, this arrangement permits only line contact between the rollers and the helix shaft, which arrangement creates less friction or resisting force to the 35 expansion and contraction of the metallic bellows and consequent rotation of the helix shaft than any other known arrangement.

In order to permit an adjustment between the 40 shaft 22 and the hollow metering valve the pinion 20 and the gear 21 may be removed and other of these members of relatively different sizes placed thereon by means of attaching screws or bolts 34. In order to provide an outlet for the oil bled 45 through the slots 14 and 18 there is a bleed outlet 35. There is also an outlet 36 for any oil that may pass by the piston 11 into the part of the cylinder occupied by the spring 15. There is also provided an outlet 37 for any oil that may leak 50 out through the upper end of the hollow metering valve. All of these outlets lead into a pipe that conducts the oil back to the inlet side of the oil pump, the outlet side of which is connected to the oil inlet 16.

55 In order to operate the fuel charger independently of the piston rod 8 there is provided a fuel injector lever 38. This lever may be operated by any suitable hand means, and may be so positioned that all inlets to the cylinders are cut off. 60 Also, this fuel injection lever may be used for starting purposes. When this lever is in the extreme left-hand position the fuel charger is in such position that the greatest amount of gas is delivered to the cylinders of the engine, whereas 65 if the bracket 7 is removed to a dotted line position, as shown in Figure 2, the gasoline inlets to the engine cylinders are all closed so that no fuel can be admitted into the cylinders, and in order to admit fuel the fuel injector lever must be moved toward the left-hand, as shown in Figure 2.

The spring 15 serves two purposes, the first being to counteract the oil pressure in the cylinder 12; the other to prevent the delivery of fuel from 75 the injector after the engine has been stopped.

This acts as a safety device to prevent persons from starting the engine accidentally by cranking the engine with the ignition switch on. The numeral 39 indicates a pressure inlet connecting the pressure chamber to the induction system of the engine, or to any device actuated by the engine so as to create pressure or suction.

When the pressure in the pressure chamber is at a certain condition the shaft 22 and the hollow metering valve 17 are maintained in a fixed position. If the pressure in chamber 26 decreases the metallic bellows expands, thereby moving the brackets 29 along the helix shaft, thereby rotating the shaft and at the same time rotating the hollow metering valve 17. The rotation of the hollow metering valve changes the position of the slot 18 with regard to the slot 14. If this relative change of position causes the opening between these two slots to be entirely closed, due to the piston and the apron 13, pressure is built up 20 in the cylinder 12 so that the piston is forced against the spring 15. The piston is thus forced against the spring until the point where the two slots intersect is opened. That permits the pressure of the oil to be released by the oil passing into 25 the hollow metering valve.

Any movement of the metallic bellows will cause a movement or rotation of shaft 22 and of the hollow metering valve. This rotation will cause a corresponding movement of the piston 11 30 so that the pressure in the cylinder is adjusted to equalize the pressure of the spring. This movement of the piston varies with the rotation of the helix shaft. This helix shaft rotates due to a variation of pressure in the pressure chamber. 35 Therefore, any variation in the pressure chamber will cause a movement of the piston 11, the rod 8, the brackets 7 and the control means for the fuel charger. By this means the fuel is regulated according to the pressure in the pressure 40 chamber 26. The amount of movement of the piston rod 8 with relation to the rotation of the helix shaft may be varied by varying the relative sizes of the pinion 20 and the gear 21. This adjustment may also be made by changing the incline of the helix of the groove 18 or by changing the angular position of the metallic bellows 27 by rotating it.

It will be understood that while in my embodiment shown I have utilized the lubrication pressure in the engine for circulation through the piston and the valve, any constant or variable pressure of a fluid or gas, whether a part of the engine system or not, may be employed.

It will be further understood that my control 55 device is applicable to any type of mechanism other than an engine, and a pressure-actuated device may be applied and connected to a region where there is either pressure or vacuum.

I desire to comprehend within my invention 60 such modifications as may be embraced within my claims and the scope of my invention.

Having thus fully described my invention, what I claim as new and desire to secure by Letters Patent, is:

65 1. In a fuel control apparatus, in combination with an internal combustion engine, a cylinder having an inlet for oil under pressure, a piston in said cylinder adapted to be moved in one direction by the oil pressure in the cylinder, a spring tending to move the piston against the oil pressure, means operated by the movement of the piston to regulate the delivery of fuel to the engine, and means operatively connected to the induction system of the engine to provide and 70 75

adjustably locate an oil outlet from the cylinder, whereby the position of the piston in the cylinder is determined.

2. In combination, a device affected by change 5 in pressure, a piston actuated by a fluid, means of supplying a fluid to the piston, a cylinder for receiving and guiding the piston and receiving the fluid, and a valve operated by said device affected by pressure cooperating with the cylinder 10 to adjustably locate an outlet from the cylinder, whereby the variations in pressure will actuate said device, actuate said valve and control the movements of said piston.

3. In combination, a device affected by the degree of pressure in a chamber associated with an engine, a cylinder, a piston in said cylinder, means connected to said piston for operating said engine, means for supplying a supply of fluid to said cylinder, and a valve operated by said device for regulating the flow of said fluid from the cylinder and cooperating with the cylinder to adjustably locate an outlet from the cylinder thereby controlling the extent to which the piston of 10 the cylinder is affected by said fluid.

JOHN F. CAMPBELL.
